UNITED STATES PATENT OFFICE.

ALFRED E. MASKREY, OF CANTON, OHIO.

PICKLING-MACHINE.

1,247,699.

Specification of Letters Patent. Patented Nov. 27, 1917.

Application filed July 14, 1917. Serial No. 180,538.

To all whom it may concern:

Be it known that I, ALFRED E. MASKREY, a subject of the King of Great Britain, residing at Canton, in the county of Stark 5 and State of Ohio, have invented a new and useful Pickling-Machine, of which the following is a specification.

My invention relates to improvements in machines for pickling and washing metal 10 plates and has more especial reference to a vertical motor driven machine provided with a counter-weight for balancing the holders and fluid operated cylinders for raising the holders out of the vats.

15 The object of my invention is the provision of a motor driven pickling machine provided with fluid cylinders arranged to raise the holders or crates out of the pickling and washing vats.

20 A further object is the provision of a pickling machine of this character provided with a counter-weight arranged to balance the holders or crates.

25 A further object is the provision of a pickling machine of the character referred to in which a vertically reciprocating ram is provided, a spider being slidably and rotatably mounted near the upper portion of said ram, holders or crates suspended from 30 said spider in suitable pickling and washing vats and fluid cylinders provided for vertically moving said spider with relation to the ram to elevate the holders or crates above the vats.

35 With these objects in view the invention consists in the novel construction and arrangement of parts, hereinafter described, illustrated in the accompanying drawings, and particularly pointed out in the appended 40 claims, it being understood that various changes in the form, proportions, size and minor details of construction may be made within the scope of the appended claims, without departing from the spirit or sacrificing any of the advantages of the invention.

In the accompanying drawings:

Figure 1 is a top plan view of a pickling machine embodying my invention.

50 Fig. 2 is a section on the line 2--2, Fig. 1.

Fig. 3 is a section on the line 3--3, Fig. 1.

Similar numerals of reference indicate corresponding parts throughout the several figures of the drawings.

55 Referring more especially to the construction illustrated in the accompanying draw-

ings, the numeral 1 indicates a cement base which is properly shaped to receive the pickling machine and vats and the driving mechanism. The numerals 2 and 3 representing pickling vats and the numeral 4 a washing vat within which the crates carrying the plates are successively immersed in the usual manner.

60 A vertical bearing 5 is centrally located upon the concrete base 1 and provided with upper and lower annular flanges 6 and 7 respectively, the lower flange 7 resting upon the concrete base and connected thereto by suitable tie-rods 8. A bushing 9 is preferably provided within the bearing 5 and mounted for vertical reciprocation therein is the ram 10 which is arranged to seat upon a suitable cushion member such as indicated at 11, springs 12 being provided to prevent 75 any shock upon the downward movement of the ram.

70 A suitable cylindrical member 13 is mounted upon the flange 6 of the bearing 5 and extends to a point adjacent the upper 80 portion of the ram, the plate 14 being carried upon the upper end of said cylinder and provided with a bearing 15, having a suitable bushing 16 through which the upper portion of the ram is located.

85 A rack bar 17 is provided adjacent the lower extremity of the ram 10 and meshes with a pinion 18 carried upon a horizontally disposed shaft 19, which extends through a suitable channel 20 formed in the 90 concrete base to a pit 21 arranged to receive the driving mechanism, suitable bearings 22 being provided for said shaft and a sprocket wheel 23 located upon the extremity thereof within the pit 21.

95 The sprocket wheel 23 is connected, by means of a pitman rod 24, with an arm 25 mounted upon the shaft of the worm wheel 26, which worm wheel meshes with a worm 27 mounted on the shaft 28 of the motor 29.

100 Mounted upon the other side of the sprocket wheel 23 is a wrist pin 30 to which is connected the piston rod 31 of a fluid compressor 32, said compressor being connected by means of a pipe 33 with any suitable fluid storage tank, not shown. A sprocket chain 34 is connected to the sprocket wheel 23 and located around said sprocket wheel, a counter-weight 35 being extended from the free extremity of said sprocket shank.

110 Fluid cylinders 36 are mounted upon the flange 6 of the bearing 5 and located within

the cylindrical member 13, said fluid cylinders being provided with suitable pistons 37, to which are connected rods 38 extending upwardly through suitable bearings 39 5 formed in the plate 14. Fluid is admitted to the lower extremities of said cylinders by means of pipes 40 which extend from the fluid tank above referred to.

A head 41 is mounted upon the upper 10 portion of the ram 10 and arranged to normally rest upon the shoulder 42 provided upon said ram, said head being arranged for slideable movement with relation to the ram and provided in its lower face with 15 suitable sockets 43 arranged to receive the upper extremities of the rods 38. The head 41 is provided with an upwardly extending cylindrical portion 44 upon which is rotatably mounted the hub 45 of the spider 46, 20 said spider being provided with four arms 47 from which are suspended by means of cables or their equivalents 48 the crates 49 which receive the sheets to be treated and are arranged to be reciprocated within the 25 vats as will be hereinafter described. A suitable ball race 50 is provided between the hub 45 and the head 41 in order that the spider may be easily rotated upon the head when desired.

30 The operation of the machine is as follows: The parts being in the position shown in Figs. 1 and 2, the crate designated by the letter A has just been removed from the washing vat 4 and the 35 sheets or plates removed therefrom. This crate is now in position to be refilled with sheets to be re-treated, after which air from the storage tank (not shown) is admitted through the pipes 40 to the cylinders 40 36, the pistons 37 being raised, the rods 38 contacting with the sockets 43 in the head 41 and raising said head the crates 49 being thus raised above the level of the vats. The spider and the crates carried thereby may 45 then be easily rotated by hand a quarter turn in the direction shown by the arrow in Fig. 1 until the crate A is suspended above the first pickling tank 2. The crate B which has been treated in the pickling 50 tank 2 is then suspended above the tank 3 in which a different pickling solution may be contained, the crate C which has just emerged from the pickling tank 3 is then suspended above the washing tank 4 and the 55 crate D which has just emerged from the washing tank is moved to the emptying and filling positions occupied by the crate A shown in Fig. 1. The air is now exhausted from the cylinders 36 allowing the plungers 60 37 to move back to the normal position shown in Fig. 2 the crates being lowered within the vats as shown in Fig. 2. The motor 29 is then operated and through the worm and worm wheel and pitman rod the 65 sprocket wheel 23 is oscillated thus oscillat-

ing the shaft 19, the pinion 18 thereon through the rock bar 17 reciprocating the ram 10 and thus reciprocating the crates 49 within the vats. The counter-weight 35 suspended from the sprocket wheel 23 thus 70 balances the shaft 19, counter-balancing the crates and the sheets carried therein and not only relieving the strain from the shaft 19 but causing the crates to be more easily and evenly reciprocated. 75

I claim:

1. In a pickling and washing machine of the character described, the combination with a plurality of vats, of a vertically movable ram, a rotary and vertically movable 80 spider mounted upon said ram, crates carried by said spider and arranged to be received within said vats and means for raising and lowering said spider upon said ram.

2. In a pickling and washing machine of 85 the character described, the combination with a plurality of vats, of a vertically movable ram, a rotary and vertically movable spider mounted upon said ram, crates carried by said spider and arranged to be received within said vat and fluid cylinders for raising and lowering said spiders upon 90 said ram.

3. In a pickling and washing machine of 95 the character described, the combination with a plurality of vats, of a vertically movable ram, a vertically movable head mounted upon said ram, a rotary spider mounted upon said head, crates carried by said spider and arranged to be received within said 100 vats and means for raising and lowering said heads upon said ram.

4. In a pickling and washing machine of the character described, the combination of a plurality of vats, of a vertically movable 105 ram, a rotary and vertically movable spider mounted upon said ram, crates carried by said spider and arranged to be received within said vats, fluid operated cylinders for raising and lowering said spider upon said ram, a motor arranged to reciprocate said ram and an air compressor operated by said motor and arranged to supply fluid to said cylinders.

5. In a pickling and washing machine of 115 the character described, the combination with a plurality of vats and a suitable support, of a vertically movable ram mounted within said support, a rotary and vertically movable spider mounted upon said ram, 120 crates carried by said spider and arranged to be received within said vats, means for raising and lowering said spider upon said arm, a rack bar provided upon said ram, a pinion meshing with said rack bar, a wheel operatively connected with said pinion, a chain located around said wheel, a weight suspended upon said chain, a motor and means interposed between said motor and said wheel for oscillating said wheel. 125 130

6. In a pickling and washing machine of the character described, the combination with a plurality of vats and a suitable support, of a vertically movable ram mounted 5 within said support, a rotary and vertically movable spider mounted upon said ram, crates carried by said spider and arranged to be received within said vats, fluid operated cylinders for raising and lowering said 10 spider upon said ram, a rack bar provided upon said ram, a pinion meshing with said rack bar, a wheel operatively connected to said pinion, a counter-weight suspended from said wheel, a motor, means interposed between said motor and said wheel for oscillating said wheels, and an air compressor operated by said motor and arranged to supply air to said fluid operated cylinders. In testimony that I claim the above, I have hereunto subscribed my name.

ALFRED E. MASKREY.
